UNITED STATES PATENT OFFICE.

ALBERT F. KENDLE, OF SYRACUSE, NEBRASKA.

ALARM-CLOCK MECHANISM.

Application filed March 27, 1925. Serial No. 18,831.

To all whom it may concern:

Be it known that I, ALBERT F. KENDLE, a citizen of the United States, and a resident of Syracuse, in the county of Otoe and State of Nebraska, have invented a new and useful Improvement in Alarm-Clock Mechanism, of which the following is a full, clear, and exact description.

My invention relates to improvements in alarm clock mechanism, and it consists in the combinations, constructions, and arrangements herein described and claimed.

An object of my invention is to provide an alarm clock mechanism in which the same driving mechanism is used for driving the hands of the clock and also for actuating the alarm mechanism.

A further object of my invention is to provide an alarm clock mechanism of the character described in which the gears are connected to each other so as to entirely do away with retaining pawls and ratchets that are usually provided in clock mechanisms of this character.

25 A further object of my invention is to provide an alarm clock mechanism of the character described in which the main spring performs a triple function in that it actuates the timing mechanism, it actuates the alarm mechanism, and it also is adapted to hold the driving gear in the proper position upon the driving shaft.

30 A further object of my invention is to provide an alarm clock mechanism of the character described which is extremely simple in construction and operation and in which the alarm mechanism is so geared to the main driving gear that it will permit the proper functioning of the time keeping mechanism.

Other objects and advantages will appear in the following specification, and the novel features of the invention will be particularly pointed out in the appended claims.

45 My invention is illustrated in the accompanying drawings, forming a part of this application, in which—

Figure 1 is a plan view of the device,

Figure 2 is a side elevation of the device,

50 Figure 3 is a section along the line 3—3 of Figure 1, and

Figure 4 is a plan view of Figure 3.

In carrying out my invention I make use of a clock mechanism comprising a frame 1. The frame 1 is composed of plates 2 and 3

that are spaced from each other by legs 4. The frame 1 carries a driving shaft 5 and it will be noted from Figure 1 that the plate 2 has a slot 6 cut therein for receiving the shaft 5. The other end of the shaft is disposed in an opening 7 in the plate 3. A plate 8 has a slot 9 therein for receiving the shaft 5. Screws 10 secure the plate 8 to the plate 2. By this construction, I am able to remove the driving shaft 5 from the frame 1.

60 The mechanism for moving the hands is of standard construction and therefore is not shown except for the showing of the driving gear 11 and gears 12. The driving gear 11 is loosely mounted upon the shaft 5 as is clearly shown in Figure 3, and is provided with a threaded hub 13 that is adapted to be screwed into a threaded bore 14 of a main spring housing 15. Figure 4 clearly shows the main spring 16 as being mounted within the housing 15 and as having its ends secured to the housing 15 and the shaft 5 by means of hooks 17 and 18 respectively. The upper end of the shaft 5 is made square at 19 and receives a winding key, not shown, 65 and the operator by means of this key is able to wind the main spring 16 so as to cause the main spring to assume the position shown in Figure 4. It will clearly appear that it is practically impossible to stretch 70 the spring along its length when it is wound up into a tight coil. It is this feature of the spring that I make use of in keeping the gear 11 at the required position on the shaft 5. The spring of course tends to expand and 75 will either rotate the housing 15 so as to actuate the clock mechanism, not shown, or will rotate the shaft 5 so as to actuate the alarm mechanism now to be described.

80 The alarm mechanism is shown in Figures 1 and 2 and is mounted upon the plate 2. An alarm drive gear 20 has a square bore 21 that is mounted upon the square shaft 19 whereby the gear will be turned when the shaft 5 is turned. Figure 1 shows 85 how the alarm drive gear 20 meshes with the pinion 22 carried by a stub-shaft 23. The stub-shaft 23 is slidably disposed in slots 24, one of the slots being in the plate 2 while the other slot is in a plate 25. The 90 slots 24 are arcuate in shape so as to cause the pinion 22 to always be in mesh with the alarm drive gear 20 even though the shaft 23 is moved from one end to the other end of the arcuate shaped slots 24. The func- 95

tion of the slots 24 and the shaft 23 slidably mounted in the slots, will be hereinafter described.

The shaft 23 carries a second alarm wheel 5 26 that is in mesh with a pinion 27 carried by a stub-shaft 28. The stub-shaft 28 is rotatably carried by the plates 2 and 25 as clearly shown in Figure 2. A third alarm wheel 29 is mounted upon the stub-shaft 28 10 and is in mesh with a pinion 30 on a stub-shaft 31. The stub-shaft 31 is operatively connected to an alarm escape.

The alarm mechanism is released by a timing gear in the clock mechanism, not shown, 15 whereby the alarm may be set for any time desired. A stop member 33 is provided for the alarm escape 32.

From the foregoing description of the 20 various parts of the device, the operation thereof may be readily understood. The operator rotates the shaft 5 when winding the spring 16 and doing so causes the alarm drive gear 20 to move the second alarm wheel 26 out of mesh with the pinion 27. 25 The gear 20 is moved in the direction of the arrow shown in Figure 1 during the winding of the spring 16 and therefore moves the shaft 23 from the full line position shown in Figure 1 into the dotted line position so 30 as to release the wheel 26 from the pinion 27. The shaft 5 may then be continuously rotated until the spring is wound up. As soon as the shaft 9 is released, the spring 16 will cause the shaft 5 to rotate the gear 20 in the reverse direction to that shown by the arrow, whereby the gear will cause the wheel 26 to again mesh with the pinion 27. The spring 16 is now ready to operate the clock mechanism and also the alarm mechanism.

40 In actuating the clock mechanism, the spring 16 rotates the housing 15, the housing in turn driving the gear 11. As heretofore stated, the housing 15 is threaded upon the hub 13 in such a manner that it will rotate the gear 11 only when the gear is moving in a direction to actuate the clock mechanism. If there is any tendency to rotate the gear 11 in the reverse direction such as that caused by the breaking of the spring 16, 45 the housing will merely rotate with respect to the gear until it unscrews itself from the hub 13 whereupon the housing is freed from the gear and may continue to rotate until the spring has spent itself without in any way harming the clock mechanism. The 50 same thing is true for the alarm mechanism because the shaft 5 will be rotated in the direction of the arrow shown in Figure 1 when a spring breaks, and will therefore merely remove the gear 26 from the pinion 27. It is therefore obvious that further rotation of the gear 26 will in no wise affect the alarm mechanism.

60 Assume now that the release trigger in the 65 clock mechanism releases the alarm mecha-

nism whereby this mechanism is free to be operated. The spring 16 tends to rotate the housing 15 and the shaft 5 as heretofore stated, and will therefore instantly rotate the shaft 5 so as to actuate the alarm mechanism. The gearing between the shaft 5 and the alarm escape is such as to have the alarm bell ring two half-minute intervals and during this time only move the gear 20 through approximately 90°. In this way the tension of the spring is slowly expended and will therefore not reduce the force exerted by the spring upon the clock mechanism to any appreciable extent. In this way I provide a single spring for actuating the clock mechanism and the alarm mechanism, this spring being of sufficient force to operate both of these mechanisms at the same time when the release trigger releases the alarm mechanism. The device is extremely simple in construction and is thoroughly efficient for the purpose intended.

I claim:

1. In a device of the type described a drive shaft, a gear loosely mounted on said drive shaft, a spring housing mounted upon said drive shaft and having a threaded connection with said gear whereby said housing will rotate said gear when said housing is rotated in one direction which will be released from said gear when rotated in the reverse direction, and a coil spring mounted within said housing and being adapted to rotate said housing so as to rotate said gear, said spring when breaking causing said housing to rotate in a direction to free the housing from the gear.

2. A device of the type described comprising a clock spring, a clock train operatively connected to one end of said spring, an alarm train, said alarm train having a stop member for preventing the normal operation of said train of alarm gears, means operatively connecting said alarm train with the other end of said spring, whereby said alarm train takes the place of the usual pawl and ratchet for preventing the unwinding of the spring, and means for permitting said alarm train connecting means to become disconnected from said spring when said spring is wound.

3. A device of the type described comprising a drive shaft, a main spring having one end connected to said drive shaft, an alarm train having a stop member for preventing the rotation of the gears in said train, an alarm driving gear carried by said shaft, a movable gear operatively connecting said alarm train to said alarm driving gear, a clock train operatively connected to the other end of said spring, and means for permitting said movable gear to disconnect said alarm train from said spring when said spring is wound.

4. A device of the type described compris-

ing a drive shaft, a main spring having one end connected to said drive shaft, an alarm train having a stop member for preventing the rotation of the gears in said train, an alarm driving gear carried by said shaft, a movable gear operatively connecting said alarm train to said alarm driving gear, a clock train operatively connected to the other end of said spring, means for permitting said movable gear to disconnect said alarm train from said spring when said spring is wound, and means for disconnecting said clock mechanism from said main spring when said spring is broken.

ALBERT F. KENDLE.
